UNITED STATES PATENT OFFICE.

JOSEPH LAWSON, OF GREAT ST. HELENS, LONDON, ENGLAND, ASSIGNOR TO ASIATIC PETROLEUM COMPANY, LIMITED, OF ST. HELENS COURT, LONDON, ENGLAND.

MEANS FOR FILLING TWO CONTAINERS ALTERNATELY.

Application filed January 3, 1928, Serial No. 244,342, and in Great Britain September 29, 1926.

- This invention relates to means for filling two containers alternately, and is particularly applicable to apparatus, such as curb-side pumps, of the type in which a plug cock or like valve automatically controls the supply of liquid to and the discharge of liquid from the containers, the said cock being actuated by increase in the pressure of the liquid when a container is filled.
- According to one feature of the present invention, the necessary movement of a plug cock to fill a pair of containers alternately and to deliver liquid therefrom is automatically effected by two cylinders, the pistons of which are directly coupled to a rocking member, such as a saddle piece or the like, having on the two end portions thereof a valve seating for controlling the admission of liquid to one or other of the cylinders, the said seatings being adapted to engage one or the other face of a double-headed valve, fast with the plug of the cock. Preferably the angular distance between the valve faces is 30° less than the angular distance between the seatings on the saddle piece, and an over-centre spring is connected to the plug or to the double-headed valve, the whole being so arranged that the pistons can cause the saddle piece, and with it the double-headed valve and plug, to turn, say 60° while the over-centre spring turns the double-headed valve, and with it the plug, a further 30° , so that the double-headed valve leaves that valve seating on the saddle piece against which it had been abutting, and comes into contact with the other valve seating, thereby preventing further admission of liquid to that cylinder which was being supplied and allowing liquid to be admitted to the other cylinder.
- Preferably the saddle piece is rotatably mounted upon an extension on the plug. The saddle piece is preferably provided with a partition which separates one cylinder from the other, whereby the pressure conditions in each cylinder are independent, whilst, in order that liquid which is discharged from one cylinder while the other cylinder is being supplied, may be led away, a pair of grooves formed in the plug and in communication with the liquid reservoir, for example, are each adapted to be placed in communication, by ports formed in the saddle piece, with that cylinder which is being discharged, and to be closed thereto by the saddle piece when the said cylinder is being supplied with liquid.
- In a modification the pistons are directly connected to a sleeve concentric with a plug valve which controls the supply of liquid to the cylinders in which the pistons are located. The sleeve is provided with an abutment which is adapted to engage one or the other of two projections on a crank to which one end of the over-centre spring is secured. The crank is also provided with projections adapted to engage between abutments formed on the plug cock, and with an abutment formed on the plug valve.
- Preferably the arrangement is such that the pistons move the crank and the plug cock through 60° , and the over-centre spring moves the plug valve through 30° and completes the necessary movement of the plug cock, thereby causing this latter to move through 90° .
- The liquid which is discharged from the cylinders is preferably led into a chamber in which the sleeve, crank and over-centre spring are located, and into which escapes any fluid which may leak past the plug cock or from a bridge which connects the containers, the chamber being placed in communication with the reservoir. This chamber may normally be at atmospheric pressure, but if the system be under air pressure it is preferably in communication therewith, thus providing back pressure to the pistons alternately and thereby automatically preventing premature reversal of the plug valve, so that it can only be reversed when a container is emptied and the pressure of the air system thereby lowered.
- Preferably the plug cock and the plug valve are arranged coaxially.
- Preferably the mechanism comprising the pistons, saddle piece or sleeve, double-headed valve or plug valve, and over-centre spring, is located in shunt between the pump and the inlet to the plug cock, whereby movement of the said mechanism does not affect the capacity of the containers.
- When the apparatus is provided with mechanism for indicating the quantity of liquid delivered, the over-centre spring is located within the casing of the plug cock, whereby

the said indicating mechanism may be removed without affecting the automatic operation of the cock.

Preferably the plug cock is formed as one unit, and the plug valve, sleeve, crank and over-centre spring are formed as a separate unit, the two units being secured together. Such an arrangement facilitates the assembly of the mechanism.

10 Preferably in order that the plug shall be free from end pressure, the end thereof passes through a bearing formed in a partition into a chamber to which access of liquid is prevented by said partition, the said chamber being maintained substantially at atmospheric pressure, which may be effected by extending the grooves formed on the plug into said chamber. In this case the inlet port in the plug and also the ports connecting the 15 container to the said inlet port and the delivery port, are formed in the periphery of the plug. Liquid which leaks past the bearing in the partition may conveniently be returned, for example, to the reservoir through 20 the said grooves.

Preferably the over-center spring is also located in the said chamber.

In a modification of this feature of the invention, means are provided for neutralizing the thrust exerted by the liquid on the 30 plug cock. This is effected by providing in the plug cock a pocket which is in communication with the liquid delivered through the inlet port to the said plug cock, and is located diametrically opposite to the said inlet port. Preferably when necessary, I provide at one end of the plug cock a chamber, closed by a piston, and in communication with the liquid delivered to the plug cock. 35 Movement of the piston is prevented by an adjustable stop and the area of the said piston is preferably such that the pressure exerted by the liquid on the end of the plug cock balances the pressure which tends to 40 produce endwise movement.

The plug cock is held on to its seating by a light spring which may conveniently be located between the end of the plug cock and the piston.

50 In place of connecting the over-centre spring directly to the plug or valve, we may connect it to a disk having pins thereon, which loosely engage recesses in the plug or valve, i. e. with a certain amount of play.

55 In a modification I interpose a floating ring between the plug or valve and the disk, the said ring being loosely connected to the said plug or valve and disk by means of pins in the one engaging recesses in the other.

60 In the accompanying drawings which illustrate the invention Figure 1 is a longitudinal section; Figure 2 is a section on the line A—A, Figure 1, and Figure 3 is a section on the line B—B, Figure 1.

15 Figure 4 is a longitudinal section of a mod-

ification; Figure 5 is a transverse section of Figure 4, looking on the larger end of the plug cock; Figure 6 is a left hand end elevation, as seen in Figure 4, of the crank and the bracket, in which the crank is pivotally mounted, and Figure 7 is a right hand end elevation of the same parts.

Figure 8 is a section on the line C—C, Figure 4; Figure 9 is a section on the line D—D, Figure 4, and Figure 10 is a transverse section of the plug valve with the plug cock and plug valve in the positions for fluid to pass to the left hand container (not shown) and the left hand cylinder in Figure 8.

Figures 11 and 12 are similar views to Figures 9 and 10 but with the plug cock and plug valve in positions for fluid to pass to the right hand container (not shown) and the right hand cylinder in Figure 8.

Figure 13 is a sectional elevation of a modification and Figure 14 an end elevation thereof.

Referring more particularly to Figures 1 to 3, 1, 2 are cylinders in which are located pistons, 3, 4, connected by connecting rods 5 to a saddle piece 6, located in a casing 7 and rotatably mounted on an extension 8 of a plug cock 9. The saddle piece 6 is provided with ports 10, 11 (see Figure 2), through which can pass liquid from a chamber 12 in communication with the liquid supply, and 13 is a valve fast with the extension 8 and provided with valve heads 14, 15, adapted alternately to close the ports 10, 11 respectively. The saddle piece 6 is also provided with a partition 16 (see Figure 2) which separates the cylinders 1 and 2. Fast with the extension 8 of the cock 9 is a lever 17 provided with pins 18 (see Figure 3) which loosely engage the walls of holes 19 formed in a ring 20, also in ring 20 are holes 21 in which are loosely engaged pins 22 carried by a plate 23 to which is secured one end of an over-centre spring 24, the other end of which is secured to a fixed pin 25. 26 are longitudinal grooves, formed in the extension 8, which extend through a partition 8^b into a chamber 27 in which the lever 17, ring 20, plate 23 and over-centre spring 24 are located, the other.

115 end of the said grooves being in communication with a circumferential groove 28 (see Figure 1) in communication with a port 29 leading to a passage 30 in communication with a reservoir. The saddle piece 6 is provided with ports 31 which alternately register with one or the other of the grooves 26 and serve thereby to exhaust the liquid in one or other of the cylinders 1, 2 to the reservoir.

120 The liquid is supplied to apparatus, comprising a pair of containers adapted alternately to be filled and discharged, from the chamber 12, through an inlet passage 32, formed, in the extension 8 and plug cock 9, and liquid is discharged therefrom through 130

a passage 33, any liquid which leaks along the surface of the plug cock being caught by the grooves 28 or by a second circumferential groove 34 (see Figure 1) and thence returned to the reservoir through the passage 30.

The extension 8 is formed with abutments 8^a (see Figure 2) which, when the cock 9 is reversed, engage a lever (not shown) which passes through an opening 7^a and which actuates indicating mechanism such as that described in my application Serial No. 244,340, filed January 3, 1928 for Indicating mechanism.

In operation, when the container corresponding to the cylinder 1 is filled, the supply of liquid thereto being maintained, the pressure of the liquid rises, and this increase in pressure is transmitted through the port 10 to the piston 3. The piston 3 is thereby raised, and the saddle piece rocked in a clockwise direction (see Figure 2), the cock 9, piston 4 and valve 13 moving therewith. During this operation, the over-centre spring 24 is tensioned, until when the spring passes the dead centre position, it moves the valve 13 and the cock 9 relatively to the saddle piece, the port 10 being closed and the port 11 opened to the piston 4 in communication with the supply chamber 12, whilst the cylinder 1 is placed in communication with the reservoir through one of the ports 31 and grooves 32. Simultaneously, the inlet passage 32 is placed in communication with the container which was discharging, and the passage 33 is placed in communication with that container which was being filled, whereby the liquid in this container is delivered. When the container, which is now being supplied, is filled, the operation is repeated.

It will be seen that the plug cock 9 is not subjected to end pressure for the reason that the chamber 27, into which extends the end of the extension 8, is maintained at atmospheric pressure by the grooves 26 in communication with the reservoir.

In the modification shown in Figures 4 to 12 (in Figures 4 to 8 the parts are shown in neutral position), the pistons 3, 4 are horizontally opposed and are coupled by a rod 35 adapted to transmit motion by means of a roller 36^a to a sleeve 36 having a projection 36^b adapted to engage one or other of a pair of abutments 37, 38 (see Figure 7) formed on a crank 23' to which one end of the over-centre spring 24 is attached, the crank 23' being pivotally mounted in a bracket 39 carried by the casing 7. The crank 23' is also provided with abutments 40, 41 (see Figure 7) adapted to engage a projection 42 formed on a plug valve 43, coaxial with respect to the plug cock 9, and provided with passages 44, 45 which register at one end with ports 46, 47 formed in the casing, and which respectively are open to a supply passage 48 in communication with the inlet to the plug cock 9, and

a chamber 49 in communication through a passage 50 (see Figure 8) with the reservoir. The ports 46, 47 respectively are in communication with the cylinders 1, 2. The crank 23' is also provided with a projection or tooth 51 which is located between projections 52 formed on the plug cock 9 and whose movement is controlled by the stops 39^a (see Figure 6) at the ends of the bracket 39.

53 (see Figure 4) is a passage which places the chamber 49 in communication with a bridge piece (not shown) connecting the two containers, the arrangement being such that when one container is being filled, the air therein is displaced and compressed, the pressure of the air being transmitted to the chamber 49 and hence through the passage 45 to the rear of one or other of the pistons 3, 4. When the other container is completely discharged, the bridge piece becomes open to the atmosphere and hence the pressure of the air system falls to atmospheric pressure, and therefore the pressure at the rear of one or other of the pistons 3, 4 also falls to that of the atmosphere.

In order to neutralize the thrust exerted by the liquid on the plug cock 9, the said cock is formed with a pocket 54 diametrically opposite the passage 32 and in communication through a passage 55 with the said inlet passage 32.

The passage 55 is extended in one direction to the periphery of the plug cock and is of such dimensions that it is in communication with an inlet port 56 even when the inlet passage 32 is, owing to the movement of the cock, out of communication with said port 56.

Thus, it will be seen that the pocket 54 is always in communication with the liquid delivered to the port 56.

57 (see Figure 4) is a chamber formed at the rear or wide end of the cock and in communication, by means of a passage 58, with the passage 55, whilst the chamber is closed by a piston 59 between which and the end of the plug cock 9 is inserted a light spring 60; the arrangement is such that the thrust exerted by the liquid on the plug and tending to move it from its seating, is balanced by the opposite thrust due to the pressure area of the pocket 54 and that of the chamber 57.

The piston 59 is provided with a screw 61, the head of which abuts against an adjustable screw 62 carried by a bracket 63 secured to the casing.

When the apparatus is provided with mechanism such as that described in my application No. 244,340, for indicating the quantity of liquid delivered, the plug cock 9 is formed with projections 64 (see Figure 5) adapted, when the cock is reversed, alternately to engage a glandless transmitting device, such as described in my application No. 244,340 and comprising a cap 65 to which is secured one end of a flexible metallic tube 66, 130

the other end of which is secured to a plug 67 screwed into the casing. 68 is a rod, the upper end of which extends to the upper end of the tube 66, and the lower end of which is 5 adapted to enter a socket formed in a pivoted lever adapted, when the rod 68 is rocked by the projections 64, to actuate the mechanism described in the said application No. 244,340.

In operation, when the pressure of the 10 liquid is increased, due to the filling of a container, the said increase in pressure is transmitted to the rear of the piston 3 through the passage 48, valve passage 44 and port 46; since, however, the chamber 49, and hence the 15 rear of the piston 4, are subjected to the pressure of the air system of the apparatus, the piston 4, and hence the piston 3, are prevented from moving until when the discharging container is empty, the air pressure falls.

20 Movement of the piston 3 (and hence of piston 4) rocks the crank 23' in an anti-clockwise direction and the motion of the crank is transmitted to the plug cock 9 by the projections 51 and 52, the over-centre spring being 25 tensioned by the movement of the crank.

When the over-centre spring 24 has been moved beyond its dead centre position, the crank 23' is moved thereby and at the same time the abutment 41 engages the projection 30 42, the spring 24 thus reversing the valve 43 and completing the reversal of the plug cock 9. Reversal of the valve 43 places the passage 48 in communication with the rear of the piston 4 and the chamber 49 in communication 35 with the rear of the piston 3, whereby the liquid in the cylinder 1 is exhausted.

During the movement of the plug cock 9, one of the projections 64 moves against the 40 cap 65, whereby the rod 68 is rocked and the indicating mechanism, such as is described in my application No. 244,340, is actuated. The arrangement preferably is such that the projection 64 does not engage the cap 65 until the over-centre spring 24 commences to move 45 the plug cock 9.

As in the arrangement shown in Figures 1 to 3, reversal of the plug cock 9 places that container, which was being supplied with liquid through the passage 32, into communication with the discharge passage 33, and at 50 the same time the passage 32 is placed in communication with that container which was being discharged, whereby the said container is supplied with liquid. When this latter 55 container is filled, and the other container is emptied, the operation above described is repeated.

It will be seen that the casing 7, Figure 4, is formed in two units, one of which 60 comprises the plug cock 9, and the other the plug valve 43, the sleeve 36, over-centre spring 24 and crank 23', the two units being secured together at 69.

It will also be seen that the mechanism comprising the pistons 3, 4, valve 13 (Figures

1 to 3) or plug valve 43 (Figures 4 to 12) and over-centre spring 24, are located in shunt between the liquid supply and the inlet to the plug cock 9, whereby movement of the said mechanism does not affect the capacity of 70 the containers.

In the modification shown in Figures 13 and 14, the abutments 64 are replaced by a cam 70 integral with the plug cock 9, and 71 75 is a cam sheath provided with projections 72 adapted to be engaged by the cam 70 which is so shaped as gradually to move into engagement with the said projections, in the manner described in my application No. 244,340.

The sheath rod 73 is recessed to pass over the cap 65 to which the flexible tube 66 is secured.

In operation, when the cock 9 is reversed, the cam 70 moves gradually into engagement 85 with the cam sheath 71 and the rod 68 is rocked, the indicating mechanism being thereby actuated.

What I claim is:—

1. In combination, a plug cock adapted to 90 control the supply and discharge of liquid from supply means to and from a pair of containers, two cylinders, means adapted to place the cylinders alternately in communication with said liquid supply means, pistons in said cylinders, a rocking member, means connecting said rocking member to said pistons, said rocking member being adapted upon actuation of said pistons to initially and partially actuate said plug cock, and means adapted to complete the actuation of said plug cock and to actuate the means adapted to place the cylinders alternately in communication with said liquid supply means. 95

2. In combination, a plug cock adapted to 100 control the supply and discharge of liquid from supply means to and from a pair of containers, two cylinders, means adapted to place the cylinders alternately in communication with said liquid supply means, pistons in said cylinders, a rocking member, means connecting said rocking member to said pistons, said rocking member being adapted upon actuation of said pistons to initially 105 and partially actuate said plug cock, and an over-centre spring mechanism adapted to complete the actuation of said plug cock and to actuate the means adapted to place the cylinders alternately in communication with 110 said liquid supply means. 115

3. In combination, a plug cock adapted to 120 control the supply and discharge of liquid from supply means to and from a pair of containers, two cylinders, a plug valve 125 adapted to place said cylinders alternately in communication with said liquid supply means, pistons in said cylinders, a rocking member, means connecting said pistons to said rocking member, said rocking member 130

being adapted to initially and partially actuate said plug cock, and an over-centre spring mechanism adapted to complete the actuation of said plug cock and to actuate 5 said plug valve.

4. In combination, a plug cock adapted to control the supply and discharge of liquid from supply means to and from a pair of containers, two cylinders, a plug valve 10 adapted to place said cylinders alternately in communication with said liquid supply means, pistons in said cylinders, a rocking member, means connecting said pistons to said rocking member, a crank, means on said 15 rocking member adapted to engage said crank, means on said crank adapted to engage said plug cock, said rocking member being adapted to initially and partially actuate said plug cock, means on said crank adapted to 20 engage said plug valve, and an over-centre spring mechanism adapted to complete the actuation of said plug cock and to actuate said plug valve.

5. In combination, a plug cock adapted to 25 control the supply and discharge of liquid from supply means to and from a pair of containers, two cylinders, means adapted to place said cylinders alternately in communication with said liquid supply means, connecting means adapted for connection to the upper ends of said containers so that the air displaced by the liquid entering one container is forced to said other container and said connecting means, means adapted to place 30 that cylinder which is not in communication with the liquid supply means into communication with said connecting means, pistons in said cylinders, a rocking member, means connecting said rocking member to said pistons, said rocking member being adapted upon actuation of said pistons to initially and partially actuate said plug cock, and means adapted to complete the actuation of said 35 plug cock and to actuate the means adapted to place the cylinders alternately in communication with said liquid supply means.

6. In combination, a plug cock adapted to 40 control the supply and discharge of liquid from supply means to and from a pair of containers, two cylinders, means adapted to place said cylinders alternately in communication with said liquid supply means, connecting means adapted for connection to the upper ends of said containers so that the air displaced by the liquid entering one container is forced to said other container and said connecting means, means adapted to place that cylinder which is not in communication 45 with the liquid supply means into communication with said connecting means, pistons in said cylinders, a rocking member, means connecting said rocking member to said pistons, said rocking member being adapted upon actuation of said pistons to initially and partially actuate said plug cock, and means adapted to complete the actuation of said plug cock and to actuate the means adapted to place the cylinders alternately in communication with said liquid supply means.

and an over-centre spring mechanism adapted to complete the actuation of said plug cock and to actuate the means adapted to place the cylinders alternately in communication with said liquid supply means. 70

7. In combination, a plug cock adapted to control the supply and discharge of liquid from supply means to and from a pair of containers, two cylinders, a plug valve adapted to place said cylinders alternately in communication with said liquid supply means, connecting means adapted for connection to the upper ends of said containers so that the air displaced by the liquid entering one container is forced to said other container and said connecting means, means adapted to place that cylinder which is not in communication with the liquid supply means into communication with said connecting means, pistons in said cylinders, a rocking member, 75 means connecting said pistons to said rocking member, said rocking member being adapted to initially and partially actuate said plug cock, and an over-centre spring mechanism adapted to complete the actuation of said 80 plug cock and to actuate said plug valve.

8. In combination, a plug cock adapted to control the supply and discharge of liquid from supply means to and from a pair of containers, two cylinders, a plug valve adapted to place said cylinders alternately in communication with said liquid supply means, connecting means adapted for connection to the upper ends of said containers so that the air displaced by the liquid entering one container is forced to said other container and said connecting means, means adapted to place that cylinder which is not in communication with the liquid supply means into communication with said connecting means, 85 pistons in said cylinders, a rocking member, means connecting said pistons to said rocking member, a crank, means on said rocking member adapted to engage said crank, means on said crank adapted to engage said plug cock, 90 said rocking member being adapted to initially and partially actuate said plug cock, and an over-centre spring mechanism adapted to complete the actuation of said plug cock and to actuate said plug valve.

9. In combination, a plug cock adapted to control the supply and discharge of liquid from supply means to and from a pair of containers, two cylinders, means adapted to place said cylinders alternately in communication with said liquid supply means, pistons in said cylinders, a rocking member, means connecting said rocking member to said pistons, said rocking member being adapted to initially and partially actuate said plug cock, means adapted to complete the actuation of said plug cock and to actuate said means adapted to place the cylinders alternately in communication with the liquid supply means, 100 105 110 115 120 125 130

and loosely engaging means adapted to connect said means to said plug cock and said means adapted to place the cylinders in communication with the liquid supply means.

- 5 10. In combination, a plug cock adapted to control the supply and discharge of liquid from supply means to and from a pair of containers, two cylinders, exhaust means, a plug valve adapted to place said cylinders alternately in communication with said liquid supply means and with said exhaust means, pistons in said cylinders, a rocking member, means connecting said pistons to said rocking member, said rocking member being adapted to initially and partially actuate said plug cock, and an over-centre spring mechanism adapted to complete the actuation of said plug cock and to actuate said plug valve.

10 15. In combination, a plug cock adapted to control the supply and discharge of liquid from supply means to and from a pair of containers, a chamber into which the plug cock extends, means for preventing the access of fluid to said chamber, two cylinders, means adapted to place the cylinders alternately in communication with said liquid supply means, pistons in said cylinders, a rocking member, means connecting said rocking member to said pistons, said rocking member being adapted upon actuation of said pistons to initially and partially actuate said plug cock, and means adapted to complete the actuation of said plug cock and to actuate the means adapted to place the cylinders alternately in communication with said liquid supply means.

20 25. In combination, a plug cock adapted to control the supply and discharge of liquid from supply means to and from a pair of containers, a chamber into which the plug cock extends, means for preventing the access of fluid to said chamber, two cylinders, a plug valve adapted to place said cylinders alternately in communication with said liquid supply means, pistons in said cylinders, a rocking member, means connecting said rocking member to said pistons to said plug cock, and an over-centre spring mechanism adapted to complete the actuation of said plug cock and to actuate said plug valve.

30 35. In combination, a plug cock adapted to control the supply and discharge of liquid from supply means to and from a pair of containers, a chamber into which the plug cock extends, means for preventing the access of fluid to said chamber, two cylinders, a plug valve adapted to place said cylinders alternately in communication with said liquid supply means, pistons in said cylinders, a rocking member, means connecting said rocking member to said pistons to said plug cock, and an over-centre spring mechanism adapted to complete the actuation of said plug cock and to actuate said plug valve.

40 45. In combination, a plug cock adapted to control the supply and discharge of liquid from supply means to and from a pair of containers, a chamber into which the plug cock extends, means for preventing the access of fluid to said chamber, two cylinders, a plug valve adapted to place said cylinders alternately in communication with said liquid supply means, pistons in said cylinders, a rocking member, means connecting said rocking member to said pistons to said plug cock, and an over-centre spring mechanism adapted to complete the actuation of said plug cock and to actuate said plug valve.

50 55. In combination, a plug cock adapted to control the supply and discharge of liquid from supply means to and from a pair of containers, means located on the inlet side of said plug cock for actuating said plug cock, and comprising two cylinders, means adapted to place the cylinders alternately in communication with said liquid supply means, pistons in said cylinders, a rocking member, means connecting said rocking member to said pistons, said rocking member being adapted upon actuation of said pistons to in-

initially and partially actuate said plug cock, and means adapted to complete the actuation of said plug cock and to actuate the means adapted to place the cylinders alternately in communication with said liquid supply means. 70

14. In combination, a plug cock adapted to control the supply and discharge of liquid from supply means to and from a pair of containers, means located on the inlet side of said plug cock for actuating said plug cock, and comprising two cylinders, a plug valve adapted to place said cylinders alternately in communication with said liquid supply means, pistons in said cylinders, a rocking member, means connecting said pistons to said rocking member, said rocking member being adapted to initially and partially actuate said plug cock, and an over-centre spring mechanism adapted to complete the actuation of said plug cock and to actuate said plug valve. 75 80 85

15. In combination, a plug cock adapted to control the supply and discharge of liquid from supply means to and from a pair of containers, two cylinders, means adapted to place the cylinders alternately in communication with said liquid supply means, pistons in said cylinders, a rocking member, means connecting said rocking member to said pistons, said rocking member being adapted upon actuation of said pistons to initially and partially actuate said plug cock, and means adapted to complete the actuation of said plug cock and to actuate the means adapted to place the cylinders alternately in communication with said liquid supply means, indicator operating mechanism and fluid tight means adapted to be actuated by actuation of said plug cock and to actuate said mechanism, said fluid tight means comprising a flexible tube adapted to pass through an aperture in the plug cock casing, means for sealing one end of said tube, means for securing the other end of said tube to said casing, a motion transmitting member extending through the open end of said tube, and means adapted to actuate said motion transmitting member upon actuation of said plug cock.

16. In combination, a plug cock adapted to control the supply and discharge of liquid from supply means to and from a pair of containers, two cylinders, a plug valve adapted to place said cylinders alternately in communication with said liquid supply means, pistons in said cylinders, a rocking member, means connecting said pistons to said rocking member, said rocking member being adapted to initially and partially actuate said plug cock, and an over-centre spring mechanism adapted to complete the actuation of said plug cock and to actuate said plug valve, indicator operating mechanism and fluid tight means adapted to be actuated by

- actuation of said plug cock and to actuate said mechanism, said fluid tight means comprising a flexible tube adapted to pass through an aperture in the plug cock casing, 5 means for sealing one end of said tube, means for securing the other end of said tube to said casing, a motion transmitting member extending through the open end of said tube, and means adapted to actuate said motion 10 transmitting member upon actuation of said plug cock.
17. The combination with a plug cock adapted to control the supply of a fluid, of means for neutralizing the side thrust exerted 15 by the fluid pressure on said plug cock comprising a recess located in the side of the plug.
18. The combination with a tapered plug cock adapted to control the supply of a fluid, of means for neutralizing the side thrust exerted 20 by the fluid pressure on said plug cock comprising a recess located in the side of the plug, and means for opposing end thrust exerted by the fluid pressure.
19. The combination with a plug cock 25 adapted to control the supply of fluid, of means for neutralizing the side thrust exerted by the liquid on said plug cock, comprising a recess in the side of the plug, and means for placing said recess in communication with the fluid supply to said cock.
20. The combination with a plug cock adapted to control the supply of a fluid, of means for neutralizing the side thrust exerted by the fluid pressure on said plug cock comprising a recess located in the side of the plug, and means for opposing end thrust exerted by the fluid pressure, comprising a chamber located at one end of said plug cock, means adapted to seal said chamber, and means adapted to place said chamber in communication with the liquid supply to said cock.
21. The combination with a plug cock 45 adapted to control the supply of a fluid, of means for neutralizing the side thrust exerted by the fluid pressure on said plug cock comprising a recess located in the side of the plug, and means for opposing end thrust exerted by the fluid pressure, comprising a chamber located at one end of said plug cock, a piston adapted to seal said chamber, and means adapted to place said chamber in communication with the liquid supply to said cock.
22. The combination with a plug cock 55 adapted to control the supply of a fluid, of means for neutralizing the side thrust exerted by the fluid pressure on said plug cock comprising a recess located in the side of the plug, and spring means for opposing end thrust exerted by the fluid pressure.
23. The combination with a plug cock adapted to control the supply of a fluid, of means for neutralizing the side thrust exerted 60 by the fluid pressure on said plug cock comprising a recess located in the side of the plug cock and to actuate said mechanism, said fluid tight means comprising a flexible tube adapted to pass through an aperture in the plug cock casing, 5 means for sealing one end of said tube, means for securing the other end of said tube to said casing, a motion transmitting member extending through the open end of said tube, and means adapted to actuate said motion 10 transmitting member upon actuation of said plug cock.
24. The combination with a plug cock 75 adapted to control the supply of a fluid, of means for neutralizing the side thrust exerted by the fluid pressure on said plug cock comprising a recess located in the side of the plug, spring means for opposing end thrust exerted by the fluid pressure, and means for adjusting said spring.
25. The combination with a plug cock 80 adapted to control the supply of a fluid, of means for neutralizing the side thrust exerted by the fluid pressure on said plug cock, and means for opposing end thrust exerted by the fluid pressure, comprising a chamber located at one end of said plug cock, a piston adapted to seal said chamber, means adapted 85 to place said chamber in communication with the liquid supply to said cock, spring means adapted to maintain said plug cock on its seating, and means for adjusting said spring.
26. The combination with a plug cock 90 adapted to control the supply of a fluid, of means for neutralizing side thrust and end thrust exerted by the pressure of the fluid on said cock, comprising a recess, means for placing said recess in communication with the fluid supply to said cock, a chamber located at one end of said cock, means adapted to seal said chamber, and means adapted to place said chamber in communication with said fluid supply.
27. The combination with a plug cock 95 adapted to control the supply of a fluid, of means for neutralizing side thrust and end thrust exerted by the pressure of the fluid on said cock, comprising a recess, means for placing said recess in communication with the fluid supply to said cock, a chamber located at one end of said cock, a piston adapted to seal said chamber, and means adapted to place said chamber in communication with said fluid supply.
28. The combination with a plug cock 100 adapted to control the supply of a fluid, of means for neutralizing side thrust and end thrust exerted by the pressure of the fluid on said cock, comprising a recess, means for placing said recess in communication with the fluid supply to said cock, a chamber located at one end of said cock, a piston adapted to seal said chamber, means adapted to place said chamber in communication with said fluid supply, and spring means adapted to maintain said plug cock on its seating.
29. The combination with a plug cock 105 adapted to control the supply of a fluid, of

means for neutralizing side thrust and end thrust exerted by the pressure of the fluid on said cock, comprising a recess, means for placing said recess in communication with the fluid supply to said cock, a chamber located at one end of said cock, a piston adapted to seal said chamber, means adapted to place said chamber in communication with said fluid supply, spring means adapted to maintain said plug cock on its seating, and means for adjusting said spring.

30. The combination with a plug cock adapted to control the supply of a fluid, of means for neutralizing side thrust and end thrust exerted by the fluid pressure on said

cock, comprising a recess in said cock, a passage in communication with said recess and with the fluid supply to said cock, a chamber located at one end of said cock, a piston adapted to seal said chamber, a passage in communication with said chamber and said fluid supply, spring means abutting against said piston and said cock, and an adjustable thrust member against which the piston abuts. 20 25

In testimony that I claim the foregoing as my invention I have signed my name this 15th day of December, 1927.

JOSEPH LAWSON.
